DESIGN FOR A RADIO RECEIVER CABINET

Horace Terrell, New York, N. Y., assignor to Espey
Manufacturing Company, Inc., New York, N. Y.,
a corporation of New York

Application December 13, 1944, Serial No. 116,880

Term of patent 3½ years

(CL. D56—4)

To all whom it may concern:

It is known that I, Horace Terrell, a citizen of the United States, residing at New York city, county of New York, and State of New York, have invented a new, original, and ornamental Design for a Radio Receiver Cabinet, of which the following is a specification, reference being had to the accompanying drawing, forming part thereof.

The figure is a perspective view of a radio receiver cabinet embodying my new design.

The rear portion and the side portion, not shown, are plain.

The characteristic features of my design reside in the portions shown by means of full lines in the drawing.

I claim:

The ornamental design for a radio receiver cabinet, as shown and described.

HORACE TERRELL.
